Albert R. Haag, Frank W. Werckle, and Ross E. Locher, Peoria, Ill., assignors to Albert R. Haag and George A. Haag, both of Peoria, Ill., doing business as Haag Bros. Co., a copartnership

Application November 4, 1937, Serial No. 172,819

10 Claims. (Cl. 68—253)

This invention relates to clothes wringers particularly of the power operated type, said invention being directed to mechanism in connection with the release and separation of the wringer rolls.

An object of the invention is to provide a novel means by which the wringer rolls during wringing action will be more positively released when any usual hand release mechanism is operated for that purpose.

More specifically the object of the invention is to furnish mechanism whereby when any usual hand release mechanism is operated to separate the rolls the direct drive for the latter will be terminated to thereby more positively release the rolls and terminate their rotation.

Another object is to provide mechanism by means of which the gears in the usual gear box in the head of the wringer will be positively and automatically separated to thus instantly stop rotation of the wringer rolls when any usual release mechanism is operated to bring about the separation of said rolls.

Still another object is that while providing for the separation of the wringer driving gears the act of restoration of driving relation thereof will be unhindered when the wringer parts are again brought into operative condition.

To the end that the invention may be fully understood the accompanying drawings are provided wherein—

Figure 1 is a longitudinal sectional elevation of parts of a wringer structure, shown full size, wherein part of the invention is illustrated.

Figure 1^a illustrates in perspective a portion of a two-part telescoping member entering into the present invention.

Figure 2 is a plan of some of the parts shown in Figure 1, certain of them, together with other parts, being shown in section as produced on line 2—2 of said Figure 1.

Figure 3 is a transverse sectional elevation of parts shown in both Figures 1 and 2.

Figures 4, 5 and 6 are plans of parts shown in Figure 2 illustrating different positions thereof during operation.

Figure 7 illustrates in perspective one of the parts shown in the former figures.

Figure 8 is a side elevation of a structure shown in vertical section in Figure 1, and in horizontal section in Figure 2, and

Figure 9 is a side elevation of a notched shaft employed in the wringer structure.

Figure 10 is a side elevation of the wringer in part section showing the general structure.

In the figures, 1 denotes parts of the wringer frame or body which may be of a type conforming to any of the conventional forms thereof, while 2 is the usual driving pinion on a power driven shaft 3. That portion of 1 enclosing the pinion 2 and the shaft 3 may be termed the gear box. A short driven shaft 4 at right angles to the shaft 3 has its bearing at 5 and 6 on the frame 1. A collar 7 is secured to the shaft 4 by a pin and has an opening in the end opposite to the shaft 4 for the reception of the stub end of the shaft 8. This operates as a universal joint type of drive for driving the shaft 8 of a lower wringer roll 9, said shaft having a bearing at 10, for example, resting on the frame 1. Fixed to the shaft 4 but slidably therealong is a sleeve 11 carrying gears 12 and 13 to mesh with said pinion 2, comprising shiftable transmission gearing all more or less conventional. Midway of the sleeve 11, in this instance, is an annular groove 14 and directly above said groove when the gears are in "neutral" is a boss 15 depending from the frame 1 forming a bearing for a shaft 16 operated by a lever 17, said shaft at its end within the constituted gear box carrying eccentrically thereon a cam 18 having three flat faces 19, 20, 21 at an angle to each other but also paralleling the axis of the said shaft 16. Depending from the cam is a pin 22, also eccentric to the axis of the shaft 16, said pin extending into and having suspended from it a member or slide 23 lying in the groove 14 of the named sleeve 11 and within which groove it is adapted to reciprocate, said pin freely turning in said slide.

Seated in what may be termed a pocket at 24 of the frame 1 is a two-part member 25—26, the lower of the parts being identified by 25, while 26 represents an upper one, see Figure 1^a, and particularly Figure 8, there being one of such two part members at each end of the frame however. Interposed between these two parts is a spring 26' normally under compression and, due to the structure, always tending to draw said parts together. The lower member is provided with a slot 27 which communicates with an opening 28 for receiving a rock-shaft 29 paralleling the roll 9 and journaled in the walls of the frame 1 one, only, of such walls being shown in said Figure 8. The opening 28 receives the shaft 50 through the slot 27 as the said part 25 is lowered upon the same, over a reduced portion 30. The rotary adjustment of the shaft serves to so locate the portion 30 thereof that the said part 25 is fixed relative to the wall 1 as illustrated in 55 the figure named, whereas an adjustment of one-

half rotation of the shaft from the position shown permits the release of said part 25. Adjacent the reduced portion 39 is a pin 39' which upon rotation of said shaft serves to engage an abutment 30² by which the entire member 25, 26 is lifted during which time the slot 27 permits said reduced portion 39 to pass through it.

It is to be understood, that other means than that shown for securing the part 25 relative to the frame may be employed for the purpose of the present invention to be understood presently, the means illustrated being but one form suitable for the purpose.

A part of a closure member for the top of the wringer is shown at 31, this having at each end 15 a lug 32 whose upper surface is preferably slightly downwardly slanted, one of which is shown in Figure 1, the part 26 of the said two part member 25, 26 having a hook-portion 33 adapted to engage upon said lug, a portion of any usual hand wringer-release mechanism old and well known serving to maintain the hook portion 33 in position engagement with said lug. In this instance a rod 34 abuts the portion having said hook portion 33 to hold the hook on said lug 32 and which by means not necessary to show herein, serves to permit said rod to be removed from said hook portion to permit the lug 32 and top cover 31 to rise. In Figure 10, the top cover 31 is shown held down by engagement of the hook portion 33 over the lug 32. In Figure 1, the top cover 31 is shown in the same position, the position of the hook portion 33 on the lug 32 being shown in dotted lines. The full line position of the hook portion 33 shows the hook portion in the retracted position and at the moment the top cover 31 is free to rise and the hook portion 33 is free to be drawn downward by the action of the springs 26'.

An upper wringer roll 9¹, in this instance only, is shown suspended from the closure member by means of a hanger-bearing 9², though the roll may be otherwise controlled.

Upwardly extending from the lower part 25 of the said two part member, Figure 1, is a portion 25' provided with an angular surface 25² facing in the direction of the gearing previously described. Lying adjacent said surface is one end of a rod 35 whose other end, Figure 2, is slidably guided in a tubular extension 36 projecting from a boss 37 forming in this instance a part of a cover-plate 38 for the gear box, the bore of the extension 36 communicating with a bore 39 of said boss 37, the axis of which is in line with that of the described shaft 16 while lying at right angles thereto. This rod 35 functions as a communicating element between the operating gearing and the mechanism including the parts 25, 26 which are released when the top closure is released and is permitted to rise. The detailed construction and operation of these parts will be further described.

A member including a piston-like part 40, which may be designated a key member, adapted for reciprocation is slidable in said bore 39 and provided with a head 41 to abut the cam 18 as best illustrated in Figure 3, being adapted to bear against any one of the faces 19, 20, and 21 thereof, there being an expanding spring 39' in said bore 39 constantly urging the member 40 toward said cam. Preferably a ball 35' lies in the bore of the extension 36 to abut the member 40 and is also adapted to enter a notch 40' of said member adjacent said head 41. The ball serves as a freely revoluble end piece for the rod 35. The 75

rod 35 is constructed of such a length as to be held under compression between the member 40, ball 35', and the said two-part member 25-26 when the two-part member is in its normal operable position.

It may here be stated that as shown in Figure 2 when the gears 12 and 13 lie in the neutral position the forward flat face of the head 40 abuts the widest face 20 of the said cam 18 at which time the member 40 lies in such position within the boss 37 that the ball 35' lies against its side. However, when the cam is made to lie in either of the positions shown in Figures 5 and 6 due to swinging the hand lever 17 to engage one or the other of the gears with the pinion 2, the movement of said cam forces the head 41 and its member 40 compressing the spring 39' whereupon the ball 35' lies in the recess 40' as illustrated in the figures last named, it being understood from the drawings, Figure 3, that the cam since eccentrically mounted on the shaft 16 serves to shift the sleeve 11 in either direction due to the connection of the cam with the slide 23 through the pin 22.

Attention is drawn to the fact that whereas the line of thrust of the piston-like member 40 and its head 41 is directly in line with the axis of the shaft 16 and the pin 22 of the cam in Figures 2 and 4 in the neutral position of the gears, said line of thrust in Figures 5 and 6 is transferred to either side of said line of thrust or at a corner of the said head 41 and passing through the said pin only, no action of the part due to the spring 39' resulting, however, since the ball 35' lies in the recess 40'.

In the construction described, or its equivalent, for securing the part 25 of the two part member with respect to the frame 1 the upper portion 26 by means of the hook portion 33 and the lug 32 of the closure member 31 holds and tends to draw the latter elastically downward through the springs 26', any such means as a releasable rod 34 described providing for maintaining positive engagement of said hook-portion and lug as previously stated.

Figure 1 shows the gears 12, 13, in the neutral position, neither being in engagement with the driving pinion. At this stage, the rod 34 is retracted from the hook member 33 and the top cover 31 is free to rise and the catch 33 is free to be drawn down by the influence of the springs 26'. The position of the parts 26 and 33, as shown in full lines, indicates that the gears 12 and 13 are in the neutral position.

Let it be supposed, now, that one or the other of the gears 12, 13 is in mesh with the pinion 2 while the wringer is in operation, doing work, the named cam 18 at this time having shifted the head 41 to either position shown in Figures 5 and 6 where it is held by the ball 35'. When the parts 26 and 33 are in the dotted line position, as shown in Figure 1, the machine is in the operating position to do work. At this time the rod 35 holds the said ball in the position named due to abutting the inclined face 25² of the portion 25' while the part 26 has locked engagement with the lug 32 of the closure member 31 the part 25' thus being fixed so that the spring 39' at the gear box cannot act to effect the said rod 35.

When necessary to release the rolls by striking any usual release mechanism (not shown in its entirety) on the closure member the rod 34 thereof is drawn away from the portion carrying the hook-portion 33, the latter being now free to slip

off the lug 32. Due to the strain of the springs 26' the part 26 carrying said hook portion is pulled downward thus positively drawing the hook portion down over the lug said portion thus causing the two part member 25, 26 to tilt laterally away from the rod 35 the part 25' thus freeing the rod 35 and ball 35' permitting the spring 39' to operate the head 41 within the gear box. The ball 35' is pushed out of the notch 40'. During the tilting of the member 25, 26, it moves from the dotted line position (Figure 1) to the full line position shown in the same figure and in Figure 2. The head 41 thereupon operates upon the cam 18 and carrying it to the position shown in Figure 2, the gears 12, 13 thus being carried to the neutral position or entirely free of the driving pinion 2 by the action of said spring 39'. Thus while the wringer rolls have been separated by releasing the closure member carrying the upper roll, the rotation of the power driven roll has also been terminated.

Further in regard to the manner of engagement of the hook portion 33 with the lug 32, it may be noted that the engagement between those parts is unstable, the former being prevented from slipping off from the latter by the thrusting action of the arms 34 when the closure is in the operative position and the rolls are under compression. The relative positions of the hook portion 33 and the lug 32 at the moment of disengagement are represented in dotted lines. The tilted position of the members 25 and 26 is also shown in dotted lines and it will be apparent that these parts are permitted to move more at their upper portion than at the bottom, as will be clear from the dotted line position.

In restoring the parts to operating position the rock shaft 29 is rotated to raise the two part member 25, 26 so that the hook portion 33 may be reengaged with the lug 32 of the closure member whereupon a rotation of the rock-shaft will permit the part 25 to lower, the corner of the reduced portion 38 of said shaft engaging the said part 25 at the slot 27 drawing the part down to the position shown in Figure 8, while the hook portion of the part 26, however, remains in engagement with said lug 32. This action restores the portion 25' to position and bears against the rod 35 to carry the ball 35' toward the bore 38, the ball lying against the member 40 and free to enter the notch 40' to lock the head in either position shown in Figures 5 and 6 with the gearing in mesh.

While the rod 35 has been described as having a bearing at one end upon the part 25' having the angular surface 25', it is to be understood that said rod may bear against any other part corresponding in result to that produced by said part 25'.

A form of mechanism has been illustrated and described herein which serves to bring about the neutral relation of the gears that drive the rolls when operating the wringer-roll release mechanism, but it is understood that it is not the desire or intent to be confined thereto since other means may perhaps be employed to serve in a like capacity. And, of course, any desired type of wringer roll release mechanism may be employed to accomplish the end sought. In some of the claims the ball 35' and the rod 35 will be referred to by the term "means" in the interest of brevity.

What is claimed is:

1. In a power driven wringer, including its frame, rolls therein and means for providing pressure between said rolls, the combination with

a power driven gear, a pair of gears to separately mesh with the latter for operating the wringer rolls and including a shifting sleeve, and manually operated means for bringing about the separation of the rolls, of mechanism including a slide engaging in the sleeve and shiftable at right angles to the axis of sleeve rotation, a cam swingable eccentrically on a shaft mounted in the wringer frame, a pin on said cam mounted on 10 said cam eccentrically to the axis of the said shaft, said cam having three faces each corresponding in position to one of the three shifted positions of the pair of gears, a shiftable member guided in the wringer frame structure arranged 15 to reciprocate in a direction at right angles to the axis of rotation of said pair of gears and adapted to abut a face of said cam, a spring constantly urging the member in the direction of the cam, a mounted shiftable rod interposed between the member and the manually operated 20 wringer roll release means and engageable at one end with the latter, a ball interposed between the other end of the rod and said member, there being a notch in the latter to receive the ball in 25 given position of that member with respect to the cam.

2. In a power driven wringer, including its frame, rolls therein, and means for providing pressure between said rolls, the combination with 30 a power driven gear, a pair of gears to separately mesh with the latter for operating the wringer rolls and including a shifting sleeve, and manually operated means for bringing about the separation of the rolls, of mechanism including a 35 slide engaging in the sleeve for positively shifting it, said slide being shiftable at right angles to the axis of sleeve rotation, a cam swingably in the wringer frame in a plane paralleling the line of shift of said slide and eccentrically to the axis 40 of its mounting, a shiftable member guided in the wringer frame structure, a spring constantly urging the member toward the cam, said cam having a face corresponding to the neutral position 45 of the two gears of said pair of gears, and also having two other faces each corresponding to one of the positions of the gears when engaged with said power driven gear, said cam including a pin having a bearing in the named slide, and means 50 engageable with the member to hold the same from movement when said member is in a position of engagement with a face of the cam, and adapted to release said member to permit it to swing said cam on its mounting and to lie upon another face thereof after being swung.

3. In a power wringer, the combination with a power driven gear, and a pair of gears, including a sleeve, said pair of gears adapted to separately mesh with said driven gear, of mechanism including a slide engaged in and shiftable with respect to the sleeve at right angles to the axis of sleeve rotation, a cam, a mounting eccentric thereto carried in the wringer frame structure, a pin extending from the cam and also eccentric to the mounting and engaging in the said slide, a shiftable member guided in the wringer frame structure adapted to move in a line passing through the axis of the cam mounting and having a flat face, a spring urging the member toward said cam, the latter having three faces, one of them adapted to receive the flat face of the said member against it in the neutral position of the said pair of gears, each of the other faces of the cam adapted to receive the member against it in the meshing rotation of the power driven gear and a gear of said pair of gears, and a releasable part 75

to engage and hold the member in a retracted position when it engages one of the last named faces.

4. In a power wringer, the combination with a power driven gear, and a pair of gears, including a sleeve, said pair of gears adapted to separately mesh with said driven gear, of mechanism including a slide engaged in and shiftable with respect to the sleeve at right angles to the axis of sleeve rotation, a cam, a mounting eccentric thereto carried in the wringer frame structure, a pin extending from the cam and also eccentric to the mounting and engaging in the said slide, a shiftable member guided in the wringer frame structure adapted to move in a line passing through the axis of the cam mounting and having a flat face, a spring urging the member toward said cam, the latter having three faces, one of them adapted to receive the flat face of the said member against it in the neutral position of the said pair of gears, each of the other faces of the cam adapted to receive the member against it in the meshing relation of the power driven gear and a gear of said pair of gears, a part at said member to engage and hold it in retracted position when it is in engagement with one of the last named faces, and means operated to release said part for releasing said member.

5. In a power wringer including a frame and a closure member at its top, rolls in said frame, means for providing pressure between the rolls, and gearing for driving said rolls including a gear shift sleeve, in combination, a lug mounted in the closure member, a structure erected in the frame attached at one end thereto normally, its other end having a portion to engage upon the top of the named lug, said structure being adapted to normally exert a yielding downward pressure on said lug, and also adapted to have a lateral tilting action away from the latter, a manually releasable part normally abutting the portion to maintain lug engagement of the latter, mechanism in control of said gear shift sleeve, means constantly tending to operate the sleeve to shift it to neutral position, means lying between and engaging a part of the sleeve control mechanism and the named structure when the latter is in its lug engaging position normally maintaining the gearing in wringer roll driving engagement, and adapted when the manually operated part is released to release the said sleeve control mechanism in the lateral tilt of the named structure and permit the last named mechanism to move the sleeve to said neutral position.

6. In a power wringer including its frame and a closure member at its top, rolls in said frame, means for providing pressure between the rolls, and gearing for driving the rolls including a gear shift sleeve, in combination a lug mounted on the closure member, a structure erected in the frame normally attached at one end thereto, its other end having a portion to engage upon the lug, said structure being adapted to normally exert a yielding downward pull on said lug, and also adapted to have lateral tilting action away from the latter, a manually releasable part normally abutting the said portion of the structure to maintain lug engagement with the latter, mechanism in control of the gear shift sleeve, means constantly tending to operate the sleeve to shift it to neutral position, means lying between a part of the sleeve control mechanism and the named structure and engaging both when the latter is in its lug engaging position, that part of the structure engaged by the last named means

normally overhanging an extremity of such means and being inclined downwardly away from the position of the same, adapted when the manually operated part is released to release said sleeve control mechanism in the lateral tilt of the named structure and permit the last named mechanism to move the sleeve to said neutral position.

7. In a power wringer structure, the combination with the wringer frame, rolls therein, and driving gearing therefor, and a mounted shiftable sleeve having a pair of gears fixed thereon to separately mesh with the driving gearing, of a member engageable with the sleeve and shiftable with respect thereto in a line substantially at right angles to the axis of sleeve rotation, said member adapted to shift the sleeve axially along its mounting, a shaft journaled in the frame including a cam eccentrically mounted adjacent the member and having faces lying at an angle to each other each in a plane substantially paralleling the axis of the shaft, an extension carried by the cam at its side adjacent the member and disposed eccentrically to the axis of the shaft, said extension extending into the member to rotate therein, a part mounted and guided in the wringer frame in a line cutting the axis of the shaft, means to urge the part elastically against a face of the cam and to shift the sleeve by engagement with one of the said faces, and means to engage and hold the part in a given position with respect to said cam.

8. In a wringer structure, in combination with a wringer frame, a top closure therefor, wringer rolls, the pressure on one of which rolls is controlled by said closure so that said roll is held in the operative wringing position when said closure is locked down with respect to said frame, gearing for the rolls including a driving gear and driven gears, a tiltable part to normally releasably engage said closure and secure it lockably upon said frame and adapted to be disengaged from said closure to release the latter from said frame and to release the said wringer roll controlled by said closure, a key member shiftable with respect to said driving gear whereby rotation of said rolls may be controlled and reversed, manual means for shifting said key member, and a second means for controlling said key member and controlled by said top closure, including a rod wholly interposed between said key member and said tiltable part in position to co-operate with both and under compression between both said key member and said tiltable part in one position of said key member and in which position said driving and driven gears are in power transmitting relation.

9. In a wringer structure, in combination with a wringer frame, a top closure therefor, wringer rolls, the pressure on one of which rolls is controlled by said closure so that said roll is held in the operative wringing position when said closure is locked down with respect to said frame, gearing for the rolls including a driving gear and driven gears, a movable part to normally releasably engage said closure and secure it lockably upon said frame and adapted to be disengaged from said closure to release the latter from said frame and to release the said wringer roll controlled by said closure, a key member mounted for straight line horizontal movement and shiftable with respect to said driving gear whereby rotation of said rolls may be controlled and reversed, manual means for shifting said key member, and a second means for controlling said key

member and controlled by said top closure wholly interposed between said key member and said movable part and shiftably mounted to cooperate with both said key member and said movable part in one position of said key member and in which position said driving and driven gears are in power transmitting relation.

10. In a wringer structure, in combination with a wringer frame, a top closure therefor, wringer rolls, the pressure on one of which rolls is controlled by said closure so that said roll is held in the operative wringing position when said closure is locked down with respect to said frame, gearing for the rolls including a driving gear and driven gears, a movable part to normally releasably engage said closure and secure it lockably upon said frame and adapted to be disengaged from said closure to release the latter from said frame and to release the said wringer roll

controlled by said closure, a key member mounted for straight line movement and shiftably with respect to said driving gear whereby rotation of said rolls may be controlled and reversed, manual 5 means for shifting said key member, and a second means for controlling said key member and controlled by said top closure wholly interposed between said key member and said movable part for movement in a straight line generally transverse to the direction of movement of said key member and shiftably mounted to cooperate with both said key member and said movable part in one position of said key member and in which position said driving and driven gears are in power transmitting relation.
